UNITED STATES PATENT OFFICE.

JOSEPH LINDBURG, OF BROOKLYN, NEW YORK, ASSIGNOR TO UNDERWOOD ELLIOTT FISHER COMPANY, OF NEW YORK, N. Y., A CORPORATION OF DELAWARE.

TYPEWRITING MACHINE.

Application filed June 30, 1924, Serial No. 723,176. Renewed June 16, 1925.

This invention relates to typewriting machines, and more particularly to devices used in connection therewith to facilitate typing cards, with special reference to library filing cards having peculiarly cut end edges. Considerable difficulty is ordinarily encountered in typing such relatively narrow cards because of their notched and perforated end edges, which interfere with the front scale and other parts of the machine, fouling thereon and becoming displaced to the annoyance of an operator and spoilation of the cards.

One of the features of this invention is in the provision of a card-holder, that can be instantly and easily applied to a typewriting machine arranged to receive the same, in which a card is positively held at its ends, parallel with the platen, and snugly against its surface central of its length.

Another feature is in the provision of means which securely lock the device to the platen at both ends, the locking means being readily released without soiling the fingers or the use of tools.

It is a further purpose to provide a wing-scale, movable into upper and lower case positions with the platen and arranged not to interfere with the card-holder; and to further provide a card-guide directly engageable on the wing-scale, which also avoids confliction.

Other features and advantages will hereinafter appear.

In the accompanying drawings,

Figure 1 is a front elevational view of the upper part of a typewriting machine, certain parts being omitted and others broken away, and showing an embodiment of the invention as applied.

Figure 2 is a transverse sectional view taken on the line 2—2 of Figure 1.

Figure 3 is a similar sectional view taken on the line 3—3 of Figure 1.

Figure 4 is a top plan view of the card-holder as attached to the platen, and showing the card about to be inserted.

Figure 5 is an enlarged fragmentary transverse sectional view of the card-holder.

In the drawings, the numeral 10 designates a fragment of a type-bar and head, actuated as usual from the keyboard of a typewriting machine to strike against a platen 11. This platen is mounted on a

shaft 12 journaled in a platen-frame having ends 13 and being provided with an ordinary twirling knob 14 for manual rotation, and a toothed line-space wheel 15 for its ordinary operation. Each type-head commonly carries two types, respectively, upper and lower case, and the platen-frame is shifted up and down by means (not shown) to bring a printing point X into registration with either type, in addition to its longitudinal letter space and return movements, as will be understood.

A card-holder 16 is composed of a thin sheet of material having a central, parallel-edged body-portion 17, curved in cross-section to conform closely to the periphery of the cylindrical platen 11, over nearly half the area of which it is disposed for at least the length of a card to be typed, such card being generally indicated by the numeral 18. The end portions 19 of the card-holder have convergently inclined edges which extend to the end of the platen and then bend at right angles to produce parallel-edged extending flanges 20, terminating in forks 21 having between them slots or recesses 22 to engage flattened portions 23 of the shaft 12, adjacent the ends of the platen, so that, as the platen is rotated, the card-holder will turn with it.

Mounted on the flanges 20, by pivots 24, are flat catches 25, their hook elements 26 being shaped to swing around the shaft 12 and maintain the card-holder in operative position, the catches being normally held in engagement by coil tension springs 27, one of the ends of each of which is secured to pins 28 set in the catches and the other ends to pins 29 set in the flanges 20 and extending outwardly through slots 30 in the catches, the swinging movements of which are limited by the length of the slots. This construction is best seen in Figure 2, which also shows knobs 31 fixed on the catches at their corners, to extend into operative positions adjacent the periphery of the platen, these knobs obviously being arranged for convenience in releasing the catches when applying or removing the card-holder.

A rectangular opening or pocket 33 is formed centrally in the body-portion 17 of the card-holder, its width being in excess of the width of the card 18, and at the ends of the opening are recesses 34 into

which the ends of the card neatly fit to be guided at their side edges, while their end edges make contact at the bottoms of the recesses, as the combined depth of the recesses and length of the opening equals the full length of the card, as can be seen in Figure 4. The bottoms of the recesses thus form side gages.

Spring clips 35 are held over the recesses 34 by rigidly securing one end 37 of each clip to the body 17 of the card-holder, these clips being bent concentrically and inset to produce clamps 38, raised at their free outer ends to constitute guides 39, overlying the opposite margins of the recesses and shaped to receive a card therebelow which may be slipped readily into the recesses and opening to rest directly upon the platen.

Thus the cards are held from movement longitudinally and laterally and retained 20 spring-pressed against the platen. When it is desired to remove the card its side edges are grasped by the fingers of an operator entered at the spaces between the card edges 25 and the edges of the opening 33, thus raising the card by drawing its ends from below the clip. The card is entered by placing it in a position as shown in Figure 4 and pressing it sidewise below the raised guides 39 30 until seated on the platen.

A wing-scale 40 of spring material is secured at its lower, offset edge by screws 41 to a floating scale frame 42, which comprises a cross-bar 43, carried by the platen shift-frame 44, and guided vertically by a pair of integral upstanding shields 45, bent upward from the lower edge of the scale and containing elongated slots 46 shaped to receive rollers 47 carried at the ends of spring 40 brackets 48 fixed by screws 49 to a type-bar segment 50. The rollers 47 have hubs 51 on each side, pressing against the slotted shields, tending to steady the floating scale frame and prevent it from moving longitudinally.

The wing-scale 40 has a central opening 52 in its upper portion through which type pass in striking the platen at the printing point X, and also contains slots 53 extending 55 in from their lower edges, permitting their lower side portions to be bent angularly outward to the offset attaching portions on the scale frame.

On the upper front surface of the scale, 55 equi-distant from the center, are fixed two button-headed studs 56 by which is engaged a card-guide 57. The card-guide is composed of a spring bow smoothly rounded on its inner surface and curved to conform to 60 the platen. The apex 58 of the card-guide is closely adjacent the platen, but springs readily over the card-holder and is provided with a finger-piece 59 by which it may be manipulated.

65 The diverging branches 60 of the bow

blend into flat pads 61 disposed over the surface of the wing-scale 40, these pads being shaped to present lateral extensions 62 engageable on the studs 56 below their heads, and downward extensions 63 to engage between the studs, their lower extensions being beveled to facilitate entry therebetween, slightly springing the branches of the bow in so doing and firmly holding the card-guide in position.

The extreme lower ends of the pads 61 are bent to form detents 64, which engage below projecting ledges 65 on the lower edge of the wing-scale, acting to retain the card-guide on the scale until forcibly removed, and the 80 ends of the card-guide extensions 62 are bent out at right angles to provide lugs 66 to make contact with the rear surface of the shields 45, the arrangement being shown in Figures 1 and 3.

It is deemed desirable to prevent a full rotation of the platen when typing such cards and permit it to turn only sufficient for the convenient entry of the cards and the typing thereon. This is accomplished by fixing rigidly at one end of the platen, pins 67 and 68, the same extending sufficiently outward to engage on opposite sides of a stop 69, at the end of an arm 70, extending from a bracket 71, secured to the adjacent platen-frame end 13.

Obviously the location of the pins will determine the amount of rotation that can be imparted, and thus the card-holder and platen are held in position ready for use 100 without unnecessary rotation.

Variations may be resorted to within the scope of the invention, and portions of the improvements may be used without others.

Having thus described my invention, I 105 claim:

1. In a typewriting machine, the combination with a platen, of a card-holder including a plate extending along the platen and conforming to the curvature thereof, said plate including an opening forming with said platen a curved pocket for the reception of a card, the upper and lower edges of the plate formed by said opening providing respectively upper and lower gages for the card, and resilient clips adjacent the opposite ends of said pocket for engaging the card over the side margins thereof to shield the side margins and to guide the card into the pocket, to bring the lower edge of the card against said lower gage, said clips also effective to press the card completely into said plate-opening, to bring the upper edge of the card against the upper gage and to hold the card by said side margins conformably against the platen.

2. In a typewriting machine, the combination with a platen, of a card-holder including a plate extending along the platen and conforming to the curvature thereof, said

plate including an opening forming with said platen a pocket for the reception of a card, the upper and lower edges of the plate formed by said opening providing respectively upper and lower gages for the card, and resilient clips adjacent the opposite ends of said pocket for engaging the card over the side margins thereof to shield the side margins and to guide the card into the pocket, to bring the lower edge of the card against said lower gage, said clips also effective to press the card into the outline of said plate-opening, to bring the upper edge of the card against the upper gage and to hold the card by said side margins conformably against the platen, said clips being inbent adjacent the top and bottom gages and extending close to the platen, whereby to hold a relatively thin card.

20 3. In a typewriting machine, the combination with a platen, of a card-holder including a plate extending along the platen and conforming to the curvature thereof, said plate including an opening forming with said platen a pocket for the reception of a card, said pocket being equal to the vertical and longitudinal dimensions of the card, whereby a gaging frame is provided to gage the card in vertical and lateral directions when inserted in the pocket, and means for pressing the card into complete gaged relation with all the gaging edges of the pocket during introduction of the card therein.

25 4. In a typewriting machine, the combination with a platen, of a card-holder including a plate extending along the platen and conforming to the curvature thereof, said plate including an opening forming with said platen a pocket for the reception of a relatively flexible card, the upper and lower edges of the plate formed by said opening providing respectively upper and lower gages for the card, and resilient clips adjacent the opposite ends of said pocket for engaging the card over the side margins thereof to shield the side margins and to guide the card into the pocket, to bring the lower edge of the card against said lower gage, said clips also effective to press the card conformably against the platen within the outline of said plate-opening, to bring the upper edge of the card against the upper gage and to hold the card by said side margins against the platen, the height of said pocket exceeding the height of the card, and providing clearance spaces adjacent the top and bottom edges thereof, so that said card may be grasped adjacent its mid-portion, for the purpose of withdrawing said card away from the platen and from beneath the clips.

30 5. In a typewriting machine, the combination with a platen, of a card-holder including a plate lying conformably along the curved surface thereof, said plate including an opening proportioned at the extreme corners thereof to snugly receive a card within the outline of the opening and enlarged intermediately to exceed the height of said card, and a spring-clip secured at one end at the lower corner of said opening at both extremities thereof and overlying the opening to provide a free clip end over each of the corresponding upper corners, said clips projecting into the opening at each extremity of the latter between the adjacent corners and being effective to snap the upper edge of a card within the upper extreme corners of said opening when the card is

inserted and the lower edge thereof caused to register with the lower corners of said plate-opening.

5. In a typewriting machine, the combination with a platen, of a card-holder including a plate extending along the platen and conforming to the curvature thereof, said plate including an opening forming with said platen a pocket for the reception of a card, said pocket being equal to the vertical and longitudinal dimensions of the card, whereby a gaging frame is provided to gage the card in vertical and lateral directions when inserted in the pocket, and means for pressing the card into complete gaged relation with all the gaging edges of the pocket during introduction of the card therein.

6. In a typewriting machine, the combination with a platen, of a card-holder including a plate extending along the platen and conforming to the curvature thereof, said plate including an opening forming with said platen a pocket for the reception of a card, said pocket being equal to the exact vertical and longitudinal dimensions of the card, and spring-clips adjacent the opposite side edges of said pocket, said clips effective to resiliently guide the card and press it into the outline of said pocket, so as to hold all of the side edges of said card in gaged relation with all of the interior edges of said pocket.

7. In a typewriting machine, the combination with a platen and a platen-shaft, of a card-holder including a plate concentrically curved to cover a portion of the platen and extending from end to end thereof, said plate having an opening to receive a card, spring clips fixed at one end to extend over the ends of the mentioned opening and shaped at their free ends to permit insertion of a card therebelow, and means to secure the plate on the platen.

8. In a typewriting machine, the combination with a platen and a platen-shaft, of a card-holder including a plate concentrically curved to cover a portion of the platen, less than half its circumference and extending throughout its length, said plate having an oblong rectangular opening at its center equal in length to a card and being reduced in width at its ends to contact with the upper and lower edges of the card, spring clips fixed at one end to the plate to extend transversely over the narrow portions of the opening, said clips being inbent to enter the opening and having their free ends slightly raised from the surface of the plate, and means to removably secure the plate closely upon the platen.

9. In a typewriting machine, the combination with a platen and a platen-shaft, of a card-holder including a plate concentrically curved to cover a portion of the platen, less than half its circumference and extending

throughout its length, said plate having an oblong rectangular opening at its center exceeding the width of a card and equal in length thereto, the ends of the opening being reduced to be equal in width to the card, spring clips riveted to the plate to extend transversely over the reduced ends of the opening, said clips being inbent to rest upon the card and having raised free ends overlying the plate on the opposite side of the opening, and means at the ends of the plate whereby it may be closely confined to the platen.

10. In a typewriting machine, the combination with a platen and a shaft having flattened portions adjacent the ends of the platen, of a card-holder including a plate curved to the radius of the platen and extending coincident therewith, said plate having an opening to receive a card and guide the card at its ends, spring clips fixed at one end to the plate and inbent to press the card against the platen, said clips having extending raised free ends under which the card 25 may be entered, forks bent at right angles from the ends of the plate to engage the squared portions of said shaft, and means to retain the forks in engagement on the shaft.

30. 11. In a typewriting machine, the combination with a platen and a shaft having flattened portions adjacent the ends of the platen, of a card-holder including a plate curved to the radius of the platen and extending coincident therewith, said plate having an opening to receive and locate a card, spring clips carried by the plate to press the ends of the card against the platen, the clips permitting the entry of the longitudinal edge of the card into the opening, said plate having convergingly inclined edges at its ends, flanges formed on the ends of the plate to extend at right angles over the ends of the platen, forks on the flanges to engage 45 the flattened portions of the shaft, and spring-actuated catches pivoted on the flanges to secure the forks in engagement.

12. In a typewriting machine, the combination with a platen and a shaft having flattened portions adjacent the ends of the platen, of a card-holder including a plate curved to the radius of the platen and extending coincident therewith, said plate having an opening to receive and locate a card, spring clips carried by the plate to press the ends of the card against the platen, the clips permitting the entry of the longi-

tudinal edge of the card into the opening, said plate having convergingly inclined edges at its ends, flanges formed on the ends of the plate to extend at right angles over the ends of the platen, forks on the flanges to engage the flattened portions of the shaft, spring-actuated catches pivoted on the flanges to engage the shaft, preventing displacement of the holder, means for limiting the movement of the catches, and knobs set in the catches by which they may be manually released.

13. In a typewriting machine, the combination with a platen and a shaft having flattened portions adjacent the ends of the platen, of a card-holder including a plate curved to the radius of the platen and extending coincident therewith, said plate having an opening to receive and locate a card, spring clips carried by the plate to press the ends of the card against the platen, the clips permitting the entry of the longitudinal edge of the card into the opening, flanged forks formed at the ends of the plate, means for detachably engaging the forks to the flattened portions of the shaft, and means to prevent rotation of the platen within a definite limit.

14. In a typewriting machine, the combination with a platen and a shaft having flattened portions adjacent the ends of the platen, of a card-holder including a plate curved to the radius of the platen and extending coincident therewith, said plate having an opening to receive and locate a card at its four edges, means for pressing a card so located against the platen, means for retaining the plate in fixed relation on the platen, means for maintaining the platen in position to receive, deliver or type a card in the holder, said last means including pins fixed in the end of the platen to extend therefrom, and a stop fixed on a part of the machine to intercept the pins upon rotation of the platen.

15. In a typewriting machine, the combination with a platen, a shaft therefor and a platen-frame in which the shaft is journaled, of a card-holder carried on the platen to rotate therewith, pins extending outward from one end of the platen, near its periphery, a stop arranged in the path of the pins, and a bracket forming part of said stop, said bracket being secured on the adjacent platen-frame and acting to prevent the platen from making a full revolution.

JOSEPH LINDBURG.
